UNITED STATES PATENT OFFICE.

FRIEDRICH GUSTAV BERNHARDT, OF LEISNIG, SAXONY, GERMANY.

INTERSECTING GILL BOX.

Application filed May 2, 1928, Serial No. 274,666, and in Germany May 12, 1927.

This invention relates to interesting gill-boxes of the kind wherein the upper set of screws and gill bars or fallers is mounted in an independent framework so as to be capable 5 of being moved vertically upwards away from the lower set.

In the gill boxes of this kind heretofore known, when the upper set of gill bars or fallers and screws is raised from the lower 10 set, the driving gear for such upper set is disconnected from the driving gear of the lower set to which the driving power is applied, and means are provided, such as a disc secured to one of the bottom screws of the 15 upper set and having a peripheral projection adapted to engage with a recess in a corresponding disc secured to the shank of the adjacent upper screw of the lower set, for enabling it to be determined when the inter- 20 engaging gear wheels of the upper and lower sets are in the proper relative positions for registering with one another when it is desired to lower the upper set back on to the lower set.

According to my invention, in order to enable the gill bars or fallers and screws of the upper set to be permanently in driving connection with the driving gear of the machine and at the same time to permit of the upper 25 set of gill bars or fallers being moved vertically away from and towards the lower set, the upper set is driven from the lower set by means of gearing which is slideable longitudinally on but is rotatable with vertical 30 shafts that are driven from the lower set of gill bars or fallers and screws, so that the upper set can be raised away from and lowered on to the lower set during the operation 35 of the machine without its being necessary 40 to make any special adjustment of the inter-engaging gear wheels of the two sets before the upper set is lowered on to the lower set.

The accompanying drawing shows one constructional form of the subject of the invention by way of example viz:

Figure 1 shows the head of an intersecting gill box made according to the invention in its closed position.

Figure 2 shows the same in its lifted off 50 position.

Figure 3 shows the whole machine in side elevation drawn to a reduced scale.

a is the upper and *b* the lower part of the intersecting gill box. The upper part *a* can be raised and lowered by turning a hand wheel *h* by means of a screw spindle *s*, and bevel wheels *r*¹ and *r*², the hand wheel *h* being connected to the bevel wheel *r*². In this operation, the upper part *a* is held by means of guides *i* on rods *d*, so that the raising and lowering can take place properly. During the raising and lowering, the two parts *a* and *b* of the intersecting gill box remain continually in engagement with their driving members, so that when the lower screws and fallers are running the needle bars or fallers, and screws of the upper part *a* move during the raising and lowering of such upper part. The driving of the upper screw and fallers is effected by two pairs of bevel wheels *z*¹, *z*². 70 The wheels *z*¹ are connected to two vertical shafts *l*. These vertical shafts *l* are provided with longitudinal grooves *n*, in which move keys or feathers *k* during the upward and downward motion of the upper part *a*. These 75 keys or feathers are mounted in the hubs *f* of the wheels *z*³ and continuously drive the wheels *z*⁴ and therewith the upper screws and fallers. The hubs *f* of the wheels *z*³ are mounted in bearings *g* which are screwed to the upper part *a*. In this manner there is a 80 continuous drive of the upper part *a* during the raising and lowering thereof, so that any special adjustment of the screws of the upper part relatively to the screws of the lower part 85 during the lowering is unnecessary and breakage and interruptions of working by reason of inaccurate adjustment of the parts by the attendant are avoided.

Having now particularly described and ascertained the nature of my said invention and in what manner the same is to be performed, I declare that what I claim is:

1. An intersecting gill box, wherein the upper set of screws and gill bars or fallers is mounted in an independent framework so as to be capable of being moved vertically upwards away from the lower set, characterized in that the upper set of gill bars or fallers and screws is driven from the lower set by 95 means of gearing which is slideable longitudinally on but is rotatable with vertical shafts that are driven from the lower set of gill bars or fallers and screws, so that the up-

per set can be raised away from and lowered on to the lower set during the operation of the machine.

2. A constructional form of the intersecting gill box claimed in claim 1, wherein the vertical shafts are provided with longitudinal grooves which engage projections in

bevel wheels that are capable of sliding along said shafts and are arranged to drive the upper gill bars or fallers and screws. ¹⁰

In testimony whereof I have signed my name to this specification.

FRIEDRICH GUSTAV BERNHARDT.
